UNITED STATES PATENT OFFICE

2,401,849

PRESSURE-VACUUM APPARATUS

Lawrence T. Ward, Newark, N. J., assignor to
 Knapp-Monarch Company, St. Louis, Mo., a
 corporation of Missouri

Continuation of application Serial No. 439,835,
 April 21, 1942. This application December 16,
 1943, Serial No. 514,451

3 Claims. (Cl. 27—24)

1

This application is a continuation of my application, Serial No. 439,835, filed April 21, 1942.

My present invention relates to a pressure-vacuum apparatus using compressed gas such as carbonic acid gas, for the purpose of creating pressure and vacuum. The apparatus is therefore useful for displacing embalming liquid into arteries and withdrawing blood from the veins of a corpse.

One object of the invention is to provide an apparatus of this character wherein embalming or similar operations may be inexpensively performed, without the necessity of manually or electrically operated pumps, by using small bulbs of compressed gas, such as Sparklet bulbs, for producing the necessary pressure in connection with the operations.

Another object is to provide an apparatus wherein the pressure on the embalming liquid may be readily controlled while using a bulb having a gas at great pressure therein, without the necessity of using expensive reducing valves to cut down the pressure.

Still another object is to provide an apparatus wherein the pressure may be nicely controlled by a needle valve arrangement and wherein a porous element of ceramic, Carborundum or the like is interposed between the compressed gas bulb and a container of embalming liquid to insure relatively slow flow of gas from the bulb as required in connection with embalming operations.

Still a further object is to provide a means to prevent greater than a predetermined pressure being applied to the embalming liquid, as when the liquid, in flowing through the blood vessel system, strikes an obstruction, so that there is no danger of swellings resulting from a build-up of pressure in the embalming liquid discharge nozzle when such obstructions are met with.

Still a further object is to provide one form of apparatus for the relatively simple operation of injecting embalming liquid by the use of a Sparklet bulb, piercing pin, pressure gauge, needle valve, and safety valve unit, which may be used in connection with an ordinary embalming liquid container or bottle with which a discharge nozzle or injection trocar is connected.

Still another object is to provide another form of the pressure-vacuum apparatus wherein a vacuum pump is utilized for the purpose of creating a vacuum in a second container into which the blood from the veins is drawn through an intake nozzle, the vacuum pump being operated by the

2

compressed gas which is thereafter used to displace the embalming liquid.

With these and other objects in view, my invention consists in the construction, arrangement and combination of the various parts of my device whereby the objects contemplated are attained, as hereinafter more fully set forth, pointed out in my claims and illustrated in the accompanying drawings, in which:

10 Figure 1 is a plan view of one form of apparatus embodying my invention and showing it related to embalming mechanism;

Figure 2 is an enlarged sectional view of the apparatus itself;

15 Figure 3 is a further enlarged sectional view on the line 3—3 of Figure 2;

Figure 4 is a sectional view similar to a portion of Figure 3 on a reduced scale, showing a slightly modified construction;

20 Figure 5 is a diagrammatic view of a pressure-vacuum apparatus of modified construction, including both a pressure and a vacuum system;

Figure 6 is a sectional view of a portion of the apparatus shown in Figure 5; and

25 Figure 7 is an enlarged sectional view on the line 7—7 of Figure 5, showing the valves of a vacuum pump thereof.

On the accompanying drawings I have used the reference numeral 10 to indicate a bulb of compressed gas, such as carbonic acid gas or carbon dioxide (CO₂).

30 The bulb 10 furnishes the pressure for operating my apparatus, as will hereinafter appear. The bulb 10 may be contained in a bulb holder 12 which screws onto a boss 13 of a body member 14. The bulb holder 12 causes the bulb to be forcibly punctured by a piercing pin 15 mounted in a bushing 16 screwed into a sleeve 17. The sleeve 17, in turn, is screwed into the boss 13. For sealing the neck of the bulb, a gasket of rubber or the like is shown at 18.

35 The embalming unit body 14 has mounted therein a pressure gauge 19 which communicates with an opening 20 which, in turn, communicates with a cross-bore 21 in the body 14. The cross-bore 21 communicates with a bore 22 in which the sleeve 17 is mounted.

40 The bushing 16 has therein a porous insert 23 of suitable material, such as fine Carborundum or ceramic, so that gas can pass through the bushing 16 only relatively slowly. After the gas passes through the insert 23 it is controlled by a valve, the seat of which is indicated at 24 and the plug for the seat at 25. The plug 25 is mounted on a stem 26, threaded at 27 in the sleeve 17 and extending through a bore 28 to a

control knob 29, at one end of the body 14. The stem 28 is packed against leakage by a packing 30 in the bore 22, backed by a spring 31 interposed between the packing and the right-hand end of the sleeve 17.

Communicating with the lateral bore 21 is a safety valve including a valve seat at 32 and a valve plug 33 seated by a spring 34. The spring 34 is backed by an adjusting sleeve 35 for the purpose of setting the safety valve at any desired pressure. The sleeve 35 is locked against movement from its adjusted position by a lock nut 36.

Also communicating with the lateral bore 21 is a hose fitting 37 with which a hose 38 is connected. The hose extends to a pipe 39 which terminates in an embalming liquid bottle 40 for the purpose of introducing gas under pressure on the surface of the embalming liquid 41 therein. The bottle 40 may be the usual glass bottle or metal tank (preferably metal, where high pressures are used) having an outlet pipe 42 connected by a hose 43 with a discharge nozzle or injection trocar 44.

In Figure 4 I show a slight modification wherein in the embalming unit body is indicated at 14^a and the piercing pin 15^a, as well as other parts corresponding to Figure 3, are labeled with the same reference characters followed by ^a.

In this form of the invention the porous insert 23^a is mounted between the discharge (right) end 30 of the sleeve 17^a and the lateral bore 21^a by mounting it in a sleeve 45 screwed into the bottle 14^a. The opening for the sleeve 45 is closed by a plug 46. Thus the ceramic insert is interposed 35 between the valve 25^a and the bore 21^a instead of between the piercing pin 15 and the valve 25.

Referring to Figures 5, 6 and 7, I show a modification wherein the compressed gas bulb 10^b is received in a holder 12^b screwed onto a fitting 47. The fitting 47 has a piercing pin 48 therein carried by a valve plug 49. The valve plug 49 is normally seated on a valve seat 50 by a spring 51. When the bulb holder 12^b is screwed into 49 position the piercing pin 48 pierces it and the gas escapes toward the valve seat 50, the gas being sealed off from the atmosphere by a gasket 18^b.

The piercing pin 48 is not hollow, as is the pin 15 of Figure 3, so that the gas escapes around the pin, and the valve 49 must be unseated from the seat 50 before the gas can pass on to the porous insert 23^b. Further screwing of the bulb holder 12^b onto the fitting 47 opens the valve 49 to the position shown in Figure 6, so that the gas can flow through the insert 23^b.

After flowing through the insert, the gas is controlled by a needle valve 52 threaded at 53 in the body 47. The needle valve 52 has a stem 54, packed at 55 and extending to the exterior of a casing 56. A control knob 57 is mounted on the stem 54 exterior of the casing 56. The parts just described in connection with Figure 6 are shown diagrammatically in Figure 5, with their positions slightly rearranged to permit of the diagrammatic showing.

The fitting 47 is threaded into a valve chest 58 wherein a slide valve 72^a cooperates with inlet ports 59 and 60 and an exhaust port 61 of the power section of a vacuum pump, indicated generally as VP. The vacuum pump has a cylinder 62 in which power pistons 63 and 64 reciprocate, 70 and has a vacuum cylinder 65 in which a piston 66 reciprocates. The pistons 63 and 64 are connected by a rack member 67 while the pistons 64 and 66 are connected by a spacer 68. The rack member 67 has its teeth meshing with a 75 gauge 19.

A gear sector 69 mounted on a cross-shaft 70. A removable handle 71 is provided for the cross-shaft 70, so that the vacuum pump VP may be operated by hand, when necessary.

The slide valve 72^a is automatically operated by a rod 72 connected thereto and extending into a chamber 73 of the rack member 67. A finger 74 of the rod 72 is adapted to be alternately engaged by opposite ends of the chamber 73 as the rack member reciprocates for properly changing the position of the slide valve 72^a to cause continuous reciprocations as long as compressed gas is fed into the valve chest 58.

The exhaust port 61 has connected therewith a fitting 75 provided with a safety valve seat 76, a connecting boss 77 and a connecting boss 78. A safety valve plug 79 is normally seated on the seat 76 by a spring 80, the tension of which is adjustable by a threaded sleeve 81 and a knurled knob 82 thereon. A pressure gauge 83 is connected with the boss 77, and a nipple 84 is connected with the boss 78. The nipple 84 is adapted to be connected by a hose 39^b extending to a pipe 39^b in the embalming liquid container 40^b, a discharge nozzle 44^b being associated therewith, the same as in Figure 1.

The vacuum section of the vacuum pump VP has a valve body 85, as shown in Figure 7, provided with an intake valve 86 and a discharge valve 87. The valve 86 communicates through a passageway 88 with a needle valve 89 on a stem 90. The stem 90 extends to the exterior of the casing 56 and has a control knob 91 thereon. The stem is packed relative to the valve body 85 by packing indicated at 92. The exhaust side of the intake valve 86 communicates through a port 93 with the interior of the vacuum cylinder 65.

A similar port 94 communicates with the interior of the vacuum cylinder 65 and with the discharge valve 87. The discharge side of this valve communicates through a vent 95 in a plug 96 with atmosphere.

PRACTICAL OPERATION

(Of the form of invention shown in Figures 1 to 4)

After a bulb 10 has been properly pierced by screwing the holder 12 onto the boss 13, the embalming operation may be performed by thrusting the discharge tube 44 into the proper artery 25 of the body of the corpse, and opening the valve 25 the proper degree for producing the desired pressure of discharge from the nozzle 44. The pressure is indicated on the gauge 19, and as long as there are no obstructions encountered by the embalming liquid, the pressure will remain substantially constant, the blood, of course, being drained out through the proper blood veins. The porous insert 23 will insure a relatively slow flow 60 of compressed gas for displacing the liquid 41, which flow must necessarily be restricted to prevent sudden pressure increases when the liquid meets an obstruction in the blood vessels. When obstructions are met, however, the pressure will gradually rise and be indicated upon the gauge 19, but will not rise to a dangerous high pressure because of the pressure relief valve 33 which, of course, is set at a pressure slightly higher than that desired for the embalming operation. Accordingly, any hissing of the relief valve 33, caused by its opening, will indicate to the operator that the pressure is higher than the desired pressure, even though he is not watching the gauge 19. The blood vessels may be manipulated

where slight swelling is evident to remove the obstruction, and the embalming operation continued.

(Of the form of invention shown in Figures 1 to 7)

Referring to Figure 5, substantially the same operation as in connection with Figure 1 occurs, as far as the discharge nozzle 44^b and the control knob 57 are concerned. Additionally, the vacuum pump creates a vacuum in a second container 40^c provided for the blood 41^c taken from the corpse. An intake nozzle 44^c is provided for this purpose, connected by a hose 43^c and a pipe 42^c to discharge into the container or bottle 40^c. The vacuum is created therein by connection of the needle valve 89 through a hose 39^c and pipe 39^c with the bottle 40^c. The intake nozzle 44^c is thrust into the proper blood vein of the corpse for withdrawal of the blood therefrom.

In connection with the apparatus shown in Figure 5, if the operator runs out of bulbs 10^b, he can manually operate the vacuum pump VP by operating the handle 71. This results in operating the vacuum pump section as well as the power section of the vacuum pump, and the power section thereupon becomes a compressor for air taken in through a spring-closed check valve 51^a. The check valve opens outwardly to prevent escape of gas, but automatically permits the intake of air at this point when the handle 71 is manually operated.

My pressure embalming apparatus eliminates the labor of hand pumping the embalming fluid, and, at the same time, gives a wide range of pressure control. The apparatus is compact and simple to operate, the power being furnished by Sparklet bulbs, which are easily and quickly applied. The initial cost of my embalming apparatus is low, as it does not include reducing valves or motor-driven compressors. The method of operation is simple, and the cost per embalming is but a few cents, as the Sparklet bulbs are relatively inexpensive. These bulbs will each dispense about a gallon of liquid, and since they contain carbonic acid gas, there is no possibility of getting air into the blood vessels, even after all the embalming liquid is displaced. CO₂ gas has the property of passing off through body tissues, and is therefore safe to use in an apparatus of the kind I disclose.

In connection with Figure 5, the compressed gas performs both the function of operating a vacuum pump, and, thereafter, the pressure is utilized for embalming liquid displacement or

utilized in any type of apparatus requiring gas under pressure. In connection with controlling the flow of the compressed gas, the use of an insert, such as 23, to restrict the flow, insures 5 against any sudden build up of undesirably high pressures while operating the apparatus. Provision is also made against excessive pressures by the use of a safety valve, without the necessity of having to provide an expensive reducing 10 valve for this purpose. Instead of embalming apparatus, the vacuum line 38^c may be connected with any other type of apparatus utilizing vacuum for its operation.

Some changes may be made in the construction and arrangement of the parts of my apparatus without departing from the real spirit and purpose of my invention, and it is my intention to cover by my claims any modified forms of structure, or use of mechanical equivalents, 15 which may be reasonably included within their scope.

I claim as my invention:

1. In a pump structure, a bulb of compressed 25 gas, means for puncturing said bulb to permit escape of the gas under pressure therefrom, a vacuum pump, pressure operated means for operating said vacuum pump by the escaping gas from said bulb, and means for conducting the exhausting gas from said pressure operated means 30 after it has operated the same to a pressure utilizing means.

2. In a pump structure, a pressure operated 35 vacuum pump, a supply of compressed gas, means for admitting gas therefrom under pressure to the pressure operated section of said vacuum pump for operating it, means for exhausting gas from said pressure operated section to a means for utilizing the gas under pressure from said exhausting means, said vacuum pump having an intake for connection with a vacuum utilizing 40 means.

3. Apparatus of the kind disclosed comprising a pressure operated vacuum pump having a power section and a vacuum pump section, a bulb of compressed gas communicating with said power section, said power section including an exhaust port having a connection for a pressure utilizing means, said vacuum pump section having an intake port and a discharge port to atmosphere, said intake port having a connection for a vacuum utilizing means to create a vacuum therefor.

LAWRENCE T. WARD.
